[57] **CLAIM**

The ornamental design for a decorative composite glass panel, substantially as shown and described.

DESCRIPTION

FIG. 1 is a front elevational view of a composite glass panel embodying our design; and

FIGS. 2, 3 and 4 are enlarged fragmentary sections taken along the lines 2—2, 3—3 and 4—4, respectively, of FIG. 1.

The dominant features of our design reside in the illustrated combination of particularly shaped pieces of transparent or translucent glass and opaque dark beading of T-shaped section between adjacent pieces of glass, at least some of which may be contrastingly colored, and some of which are edge beveled as shown, the beveled edges being present on only one surface of the panel.

FIG-1

FIG-2

FIG-3

FIG-4
